UNITED STATES PATENT OFFICE

2,575,060

ARC INTERRUPTER FOR ELECTRIC SWITCHES

Lynn H. Matthias, Fox Point, Wis., assignor to Allen-Bradley Company, Milwaukee, Wis., a corporation of Wisconsin

Application August 7, 1947, Serial No. 766,990

3 Claims. (Cl. 200—147)

1

My invention relates to arc interrupting devices for electric switches and, in particular, to an arrangement of permanent magnets in conjunction with double break contacts. It is an object of my invention to distend the occurring arcs at the switch contacts away and outwardly from the contacts into the ends of a box-like housing which encloses the stationary and movable contacts. It is also an object of my invention to use usual parts of switch gear and to arrange them in a novel form to accomplish an improved result. And, further, it is an object of my invention to provide a switch in which high interrupting capacity is obtained and in which the cost of construction is comparatively low.

My invention comprehends a structure in which a box-like housing encloses two stationary contacts and a movable contact bar to bridge the stationary contacts, and the two end walls of said box each having imbedded therein a permanent magnet abutting a ferro-magnetic base plate which supports the housing.

My invention, its object and its accomplishment in a particular instance is described in the following specification taken in connection with the following drawings:

Fig. 1 is a perspective view of the entire assembly with the cover of the enclosure broken away to better show the switch mechanism; Fig. 2 shows the switch proper in elevation and location of permanent magnets and diagram of flux lines; and Fig. 3 is a plan view of parts as shown in Fig. 2.

Referring to Fig. 1, a box-like housing designated generally by the numeral 8 encloses stationary contacts 5 and the movable contacts 6 carried by bridge bar 7. The housing 8 is mounted on a plate 4 which is a material of low magnetic reluctance such as iron or the like. The housing 8 consists of a base 15, top wall 9 and cover 11. The top wall 9 is arranged to support the stationary contacts 5 mounted on terminals 14 (see Fig. 2) and the respective brackets 10 for connection into an electric circuit. The housing 8 is closed from the front by means of cover 11 which is held in place by the nut 12 which is threaded on to screw 13 which, in turn, is fastened to plate 4.

Attached to base plate 4 is an electromagnet assembly designated generally as 20, which is made up primarily of fieldpiece 21, magnet coil 22 and armature 24. At the upper part of the armature is attached a thimble enclosure 25 on which is mounted the bridge bar 7. The thimble is arranged to slide on post 26 and within the

2

thimble is a spring not shown to provide a resilient contact pressure between stationary and movable contacts 5 and 6, respectively. Permanent magnets 30 are placed against the metal plate 4 and held in position by recesses in the base 15 of the housing 8.

With reference to Figs. 2 and 3, it will be noted that the permanent magnets have opposite polarity at corresponding ends marked N and S respectively and that therefore there is a cross flux indicated by dotted lines 31 directly in the path of the arc when the switch is in its open position. As the path of the current is in the form of a U and is traversed by the path of the flux 31 as shown, the arc is distended outwardly away from the contacts toward the side walls of the box-like housing 8. At the lower currents the arc is distended toward the side walls as indicated by the arrows 41 by the flux component 20 provided by the permanent magnets. The flux of the permanent magnets is of high value as compared to the flux produced by the current flowing. At the higher currents the flux due to the current flowing is of higher value and the arc 25 is then distended toward the end walls of the chamber as indicated by the arrows 42.

This construction is simple and efficient in that the permanent magnets are utilized with the already existing base plate 4 to create the arc attenuating flux; and also the magnets 30 do not add appreciably to the cost or size of the existing structure. In the test performance of this switch it was noted that at the lower currents the permanent magnet presumably caused arc extinction, whereas at the high current values the arc extinction was caused primarily by the magnetic blowout action of the U shape path of the current. The box-like housing encloses the switch parts and its interior surfaces aid extinction of the arc and also the walls of the housing provide a mounting means and a protective means for the permanent magnet.

While this invention has been above described by reference to a specific instance of an embodiment thereof, it is intended that the protection of Letters Patent to be granted hereon be not unnecessarily limited thereby, and that such protection extend to the substance of the advance contained in this disclosure and defined in the 50 claims hereto appended.

What I claim as my invention is as follows:

1. An electric switch comprising two terminals each having mounted at one end thereof a contact, a bridge bar having a contact on each end 55 thereof and movable to connect said stationary

contacts into circuit, said movable and stationary contacts with said terminals forming a U in circuit closed position, a box-like housing enclosing said bridge bar and stationary contacts, a ferro-magnetic plate to support said box-like housing and two bar-like permanent magnets each of which is positioned one in each sidewall of said housing with one pole abutting said ferro-magnetic plate and with the other pole in proximity to a pair of stationary and movable contacts, and said defined structure to extinguish the arc at high currents by the inherent blowout effect of the current itself and to extinguish the arc at lower currents by the effect of the permanent magnets.

2. An electric switch comprising two terminals each having mounted at one end thereof a contact, a bridge bar having a contact on each end thereof and movable to connect said stationary contacts into circuit, said movable and stationary contacts with said terminals forming a U in circuit closed position, a box-like housing enclosing said bridge bar and stationary contacts, a ferro-magnetic plate to support said box-like housing and two bar-like permanent magnets each of which is positioned one in each sidewall of said housing with one pole abutting said ferro-magnetic plate and with the other pole in proximity to a pair of stationary and movable contacts, said two bar magnets and said ferro-magnetic plate forming substantially a U-shaped magnet, with the exposed poles having opposite polarity, and said defined structure to extinguish the arc at high currents by the inherent blowout effect of the current itself and to extinguish the arc at lower currents by the effect of the permanent magnets.

3. An electric switch comprising two terminals

each having mounted at one end thereof a contact, a bridge bar having a contact on each end thereof and movable to connect said stationary contacts into circuit, said movable and stationary contacts with said terminals forming a U in circuit closed position, a box-like housing enclosing said bridge bar and stationary contacts, said housing having the side walls in proximity to a pair of stationary and movable contacts, a ferro-magnetic plate to support said box-like housing and two bar-like permanent magnets each of which is positioned one in each side wall with one pole abutting said ferro-magnetic plate and the other pole in the line joining the junctures of the stationary and movable contacts, and said defined structure to extinguish the arc at high currents by the inherent blowout effect of the current itself and to extinguish the arc at lower currents by the effect of the permanent magnet.

LYNN H. MATTHIAS.
